UNITED STATES PATENT OFFICE.

WILLIAM E. WINE, OF TOLEDO, OHIO.

SLOPE SHEET AND METHOD OF MAKING THE SAME.

Application filed March 26, 1928. Serial No. 264,605.

My invention relates to new and useful improvements in slope sheets for freight cars, and more particularly to a hood in the slope sheet, the manner in which the hood is formed in said slope sheet, and the method of making the same.

The present application is a companion to my application filed on March 13, 1928, being Serial No. 261,265. In that case, the slope sheet has a hood or crown either formed integral with the slope sheet, or has an opening formed therein through which the hood is placed and then the hood or crown riveted in place.

15 The present application, however, contemplates a slope sheet wherein an irregular shaped opening is formed in the slope sheet and certain walls about the opening bent upwardly and then at an angle to thus form the side walls and flanges of the hood, after which a cover is riveted to said flanges.

Still another object of the invention is to provide a slope sheet with a hood therein, which hood provides clearance for the truck wheels, acts as a guide for the coal when passing into the hopper as in the former case and, furthermore provides a hood wherein the side walls are struck up from the slope sheet; thus utilizing the metal that would be wasted if simply a rectangular opening were cut in the slope sheet.

Still another object of the invention consists in blocking out the metal in the slope sheet, then pressing the same to form side walls of the slope and then simply riveting a cover to the said side walls and to the slope sheet.

With these and other objects in view, the invention consists in certain new and novel arrangements and combination of parts as will be hereinafter more fully described and pointed out in the claims.

Referring now to the drawings, showing a preferred embodiment of the invention,

45 Fig. 1 is a fragmentary side elevation, partly in section, showing the slope sheet with the hood therein, the dotted lines above the wheel showing the maximum vertical movement of the wheel.

50 Fig. 2 is a fragmentary top plan view of the slope sheet showing the cover or top plate of the hood in place.

Fig. 3 is a side elevation of the hood, the slope sheet being shown in section,

Fig. 4 is a sectional view taken on line 55 4—4 of Fig. 3,

Fig. 5 is a sectional view taken on line 5—5 of Fig. 3,

Fig. 6 is a sectional view taken on line 6—6 of Fig. 3, 60

Fig. 7 is a top plan of the slope sheet, showing the manner of blocking out the side walls and flanges of the hood.

Fig. 8 is a similar view, showing the side walls and flanges bent to their final position 65 before the cover is applied, and

Fig. 9 is a sectional view taken on line 9—9 of Fig. 8.

Referring now to Fig. 1, there is shown a fragmentary portion of a car having the side 70 sill 1, the hopper 2, and the slope sheet 3 with the improved form of hood 4 which is directly over the wheel 5.

As mentioned in the companion case, it is desirable to provide a hood in each of the two 75 sections of the slope sheet so that there will be a hood over the respective two wheels of each truck, providing a clearance both for a swinging movement and a vertical movement of the wheels.

At the same time, these hoods, as shown in my other application, and in the present application, not only provide clearance for the wheels, but assist in diverting the coal into the hoppers, as the coal slides down the slope 85 sheet. In the former application, the hood or crown was either pressed integral in the slope sheet, or a rectangular opening was cut in the slope sheet and the crown or hood was passed up through the opening and then 90 riveted to the plate.

The present invention contemplates cutting an opening in the slope sheet, but the metal is so blocked out that but very little metal is wasted and a part of the metal sheet is 95 bent up to form the side walls and flanges of the hood or crown.

Referring now to Figs. 7 and 8, it will be seen that the slope sheet 3 is of somewhat irregular formation which is similar to the 100 shape shown in my companion case, and it will be remembered that two of these sections make up the one slope sheet when the sections are in position.

Now nearly centrally of this slope sheet 3, I block out the metal as at 6 to leave the oppositely curved portions, after which these portions 7 are bent upwardly on the lines 8 so that side walls 9 will be formed; after which the portions 7 will be pressed downwardly along the lines 10 so that they occupy the position as shown in Fig. 8 and form supporting flanges.

10 It will be noticed, however, in Fig. 3, that when flanges 7 and 9 are formed in position, they will also occupy the position shown in Figs. 4, 5, and 6. In other words, the curve is not a simple one or plain curve, but extends gradually from the front of the hood to its center, while at its rearward end it drops rather abruptly. As heretofore mentioned, position of the side walls 9 and the flanges or the walls 7 may be readily understood by 20 reference to Figs. 6 and 9.

It will be noticed in Fig. 8 that after the side walls 9 and the top walls 7 are in their final position, there will be left an opening which is rather pointed at its forward end, 25 as at 11, and blunt as at 12, and the width of the opening increasing as it approaches the rear wall 12.

Rivet holes 13 are provided in the flanges 7 and likewise rivet holes 14 are positioned 30 in front of the opening and to the rear thereof.

As far as the specification has proceeded, it will be seen that by blocking out and bending the metal of this central portion of the slope sheet as described, I have formed the 35 side walls 9 for the hood or crown and utilized most of the metal that would have otherwise been wasted. Furthermore, I have formed supporting flanges 7 for the top cover 15 for the hood which will now be described.

40 Referring for the moment to Fig. 2, this top is shown in position and consists of a sheet of metal somewhat longer than the opening formed in the slope sheet. At the rear edge is formed a flange 16 and rivets are 45 passed through the flange and the aforementioned holes 14 to the rear of the opening.

In a like manner, the forward end of the sheet is provided with the marginal flange 17, so that rivets may pass through the forward rivet holes 14 and through this marginal flange.

Now this top is also provided with a central upstanding rib 18 extending towards the rear of the sheet, but merging with the surface to form a plane surface as about at 19. This top also has the sloping top walls 20 extending from the opposite edges of the sheet to the central rib 18; these walls 20 also flattening out towards the rear of the 60 rib, so that at about the point 19, the top is flat or presents a plane surface as shown in Fig. 4.

It will be noticed that in Fig. 6, the side walls are relatively low and the sloping walls 65 20 are relatively steep, whereas in Fig. 5, the

side walls are relatively high, and the top walls 20 have flattened out considerably, while finally at the rear edge of the hood, the side walls are relatively low again and the top surface flat across its entire width.

70

The outline of the hood is similar to that of the companion case, but in the present application, the side walls are formed by blocking out the metal of the slope sheets and it is only necessary to make a die to press out 75 the cover 15 which may be quickly riveted into position.

The special formed flange 21 at the side edge of the slope sheet is similar to the flange shown in my companion application and is 80 thus formed so as to be turned up and be secured to the side sill 1.

It will be understood that coal will not be obstructed in its passageway to the hopper, but will be guided in its movement, and at 85 the same time clearance will be provided for the respective wheels.

From the foregoing it will be seen that I have provided a hood or crown for the slope sheets wherein the metal of the slope sheets 90 may be so cut or blocked and bent as to form the side walls and to form supporting surfaces for a cover, which latter may be easily made in a suitable die press, quickly riveted in position and the entire slope sheet and hood 95 thus formed at relatively little expense.

I am aware that it is old to form crowns or hoods in slope sheets, but I consider it new and novel to cut the metal of the slope sheet 100 so that it forms a part of the side walls and forms a support for a special form of cover.

Many slight changes might be made without departing from the spirit and scope of the invention.

Having thus described my invention what 105 I claim as new and desire to secure by Letters Patent is:

1. A slope sheet having an opening therein, the walls about the opening bent to form side walls and flanges to support a cover, 110 and a cover secured to said flanges.

2. A slope sheet having an opening therein, integral side walls of arcuate formation, inwardly extending flanges integral with the side walls, a cover plate conforming in contour to the contour of the side walls and riveted to said flanges.

3. A slope sheet having an opening therein, upstanding side walls about the opening, the said side walls provided with flanges extending toward each other, said side walls and flanges being formed by shaping the metal after the same has been blocked out, and a cover resting on said flanges riveted thereto.

4. A slope sheet having an opening therein, upstanding side walls about the opening, flanges on said upstanding side walls, said side walls and flanges being bent up from the opening and the flanges extending towards each other, the said side walls being 120 125 130

arcuate, and a cover secured to said flanges.

5. A slope sheet having a hood formed therein, said hood being open on its under surface, side walls and flanges formed integral with the slope sheets, bent up into position, and a cover plate resting on said flanges and riveted thereto.

6. A slope sheet having an opening formed therein, side walls about the opening being bent upwardly and inwardly from the sheet, the said side walls being arcuate, a cover plate provided with a central rib and sloping top walls and said cover plate riveted to said inwardly extending portion of said

15 side walls.

7. A slope sheet having a hood formed thereon, the side walls of the hood being integral with the slope sheet, supporting flanges on the side walls and integral therewith, a 20 cover plate having flanges on its opposite edges, said cover plate riveted at its opposite ends to the slope sheet and its body portion riveted to said flanges.

8. A slope sheet having a hood therein, 25 said hood comprising side walls and supporting flanges, said side walls and flanges formed integral with the slope sheet, a cover plate supported by said flanges and riveted thereto, said cover plate extending beyond the forward and rearward ends of said 30 flanges, and the opposite ends of the cover plate riveted to said slope sheet.

9. A slope sheet having an opening therein, side walls extending upwardly from said 35 opening, supporting flanges extending at an angle to said side walls, said side walls and flanges formed integral with the slope sheet, the upper surface of the side walls and flanges dropping abruptly at the rear end of the 40 plate, a cover plate having sloping top walls and a central rib, and the said sloping walls and rib merging into a plane surface at the rear end of the plate.

10. A slope sheet having an opening 45 formed therein, said opening being pointed at its front end and blunt at its rear end, the metal about the opening being bent to form vertical side walls and sloping upper edges,

integral flanges extending inwardly from said side walls and their upper surfaces changing 50 their angle of inclination throughout their length, a cover plate having sloping walls at its forward ends, and said sloping walls merging in a horizontal plane at its rear edge.

11. A slope sheet having an opening formed therein, walls at the side of the opening, flanges on said walls at their upper edge, said walls and flanges formed integral with the slope sheet, a cover plate having a central rib extending from its forward edge and merging with the plate near the rear edge thereof, said cover plate having sloping walls extending from its opposite sides to the said rib, said walls flattening out near 65 the rear edge of the plate, and the said plate secured to said flanges and said slope sheet.

12. A slope sheet provided with a hood therein, said hood comprising side walls formed integral with the slope sheet, said 70 side walls being vertical and of changing contour throughout their periphery, and a cover sheet secured to said side walls and conforming in cross section to the periphery of the side walls.

13. The method of forming a hood in a slope sheet which comprising blocking out the walls about an opening, bending said walls upwardly and then bending the upper edges of the walls inwardly to form flanges, 80 riveting a cover plate to said flanges and to said slope sheet.

14. The method of forming a hood in a slope sheet which comprising blocking out the side walls and flanges of the hood, bending said side walls upwardly and the flanges inwardly, pressing a cover plate of sufficient width to rest on said flanges and of the same contour as the contour of the side walls and flanges, and the said cover plate being longer 90 than the said side walls, and riveting the cover plate to the said flanges and to the said slope sheet.

In testimony whereof I affix my signature.

WILLIAM E. WINE.
